TREADLE OPERATED ELECTRIC SWITCH UNIT

Harry J. Collins, Jr., Bayside, Wis., assignor to Cutler-Hammer, Inc., Milwaukee, Wis., a corporation of Delaware

Filed Mar. 17, 1961, Ser. No. 64,366

Term of patent 14 years

(Cl. D26—13)

Fig. 1

Fig. 2

Fig. 3

Fig. 4

Fig. 5

Fig. 6

FIGURE 1 is an isometric view of a treadle operated electric switch unit incorporating my new design;

FIG. 2 is an elevational view of one side thereof;

FIG. 3 is a top view thereof;

FIG. 4 is an elevational view of one end thereof;

FIG. 5 is an elevational view of the opposite end thereof; and

FIG. 6 is an elevational view of the opposite side thereof.

The dominant features of my new design reside in the portions shown in solid black lines shown in the drawings.

I claim:

The ornamental design for a treadle operated electric switch unit, substantially as shown and described.
